ATTORNEY.

UNITED STATES PATENT OFFICE.

HERBERT W. SMITH, OF COON RAPIDS, IOWA.

WINDOW-SHADE BRACKET.

1,283,938.

Specification of Letters Patent.

Patented Nov. 5, 1918.

Application filed December 24, 1917. Serial No. 208,707.

To all whom it may concern:

Be it known that I, HERBERT W. SMITH, a citizen of the United States, and resident of Coon Rapids, Carroll county, Iowa, have 5 invented a new and useful Window-Shade Bracket, of which the following is a specification.

The object of this invention is to provide an improved construction for a shade or 10 curtain bracket adapted to be removably and replaceably mounted in a window frame without the use of screws, nails or other attaching media.

A further object of this invention is to 15 provide improved means for adjusting a shade or curtain bracket to different windows having elements differently spaced apart.

A further object of this invention is to 20 provide improved means for locking a window sash through the use in a given position of a window shade or curtain bracket.

My invention is an improvement on the 25 device for which Letters Patent of the United States Number 1,231,441 were granted to me June 26, 1917, and consists in the construction, arrangement and combination of elements hereinafter set forth, pointed out in my claims and illustrated by 30 the accompanying drawing, in which—

Figure 1 is an elevation of a part of the 35 left side portion of a window frame (shown conventionally) illustrating my improved device mounted therein in position for practical use. Fig. 2 is a similar elevation of the right side portion of the same window frame showing the coacting element of my improved device in position for practical use. Fig. 3 is a front elevation, Fig. 4 an 40 end elevation and Fig. 5 a cross-section on the indicated line 5—5 of Fig. 3, illustrating my improved device in detail and on an enlarged scale, the dotted lines in Fig. 3 showing positions into which certain elements 45 may be adjusted.

In the construction of the device as shown the numerals 10, 11 designate engaging members preferably made of bar metal and formed with rolls or eyes 12, 13 on opposite 50 ends, said rolls or eyes lying wholly at one side of the plane of the body of said members. A supporting bar 14 is mounted transversely of the central portions of the engaging members 10, 11 and pivots 15, 16 are mounted through and connect the supporting bar and members, said pivots being located on the median line of the supporting

bar and to one side each of the median line of the engaging members. In other words the engaging members 10, 11 are pivoted 60 eccentrically on or by means of the pivots 15, 16. The supporting bar 14 may extend any desired distance laterally from the engaging member 11 and is formed at its outer end either with a hole 17 or a lateral notch 65 18 opening upwardly therein. The hole 17 is adapted to receive the round rigid pivot commonly used in shade rollers and projecting at one end therefrom and the notch 18 is adapted to receive the angular spring- 70 actuated pivot commonly used in and projecting at the opposite end from the shade roller. I do not desire to be limited, however, to any particular construction of the attaching means at the outer end of the supporting means as the same may be varied in 75 many particulars without departing from this invention, such variation depending upon and indicated by the use to which this device is put in respect of sustaining extra- 80 neous elements.

In practical use the device is mounted in pairs one on either side of a window as illustrated in Figs. 1 and 2; the engaging members 10, 11 being located parallel with each 85 other in a groove 19 between a stop 20 and parting bead 21 of a window frame and preferably above the lower sash 22 employed in said frame, which sash is slidably mounted for travel in said groove. The extreme margins of the engaging members 10, 11 preferably are so spaced as to engage opposing faces of the stop 20 and parting bead 21, said engaging members being slightly contracted so as to position the supporting arm 90 14 inclined upwardly as shown. In such position, when downward draft or strain is applied to the outer end of the supporting arm, it tends to spread the engaging members 10, 11 and cause them to contact more 100 firmly with or bite into the opposing faces of the stop 20 and parting bead 21. Such arrangement of the engaging members and supporting arm also locates the engaging member 11 at slightly greater altitude than 105 the member 10, thus providing that an attempt to elevate the sash 22 will cause the upper rail of said sash to engage the member 10 and apply upward strain thereon; such upward strain having the effect of 110 spreading the engaging members still further without dislodging the device from the frame. Thus provision is made for utilizing the bracket or supporting device

for a window lock which will effectively prevent raising of the sash beyond a point determined by the location of the bracket.

The eccentric pivoting of the engaging members 10, 11 on the bar 14 provides for an adjustment of the lateral spacing of engaging faces of said members to compensate for differences in width of various grooves 19 or different spacings apart of stops 20 and parting beads 21; one adjustment being effected by inverting the member 10 as shown by dotted lines, thus increasing the effective width of the engaging devices by the degree of eccentric pivoting 15 of said member, and another adjustment being effected by inverting the member 11, thus contracting the effective width of the device by the degree of eccentric pivoting of said member; such adjustments being indicated by dotted lines in Fig. 3.

The brackets may be located at any desired altitude within the length of the groove 19 above the lower sash 22 and the brackets may be employed to support shade 25 rollers as indicated or any other rod, pole or device susceptible of being attached thereto.

Either bracket may be released from the frame in which it is mounted by manually 30 moving the outer end of its supporting arm upwardly through an arc, such movement being communicated to and causing the contraction or approach to each other of the engaging members 10, 11.

35 I claim as my invention—

1. A bracket, comprising engaging members arranged substantially parallel with each other, a supporting arm extending transversely of the central portions of said 40 engaging members, and spaced pivots separately connecting said supporting arm and engaging members.

2. A bracket, comprising engaging members made of bar metal and each formed 45 with a roll or eye on each end, all of the rolls or eyes lying at one side of the plane of the engaging member, a supporting arm extending transversely of the central portions of said engaging members and on the 50 opposite side thereof from said rolls or eyes, and pivots connecting said supporting arm and engaging members.

3. A bracket, comprising counterpart engaging members made of bar metal and each 55 formed with a roll or eye on each end, all of the rolls or eyes lying on one side of the plane of the engaging member, a supporting arm extending transversely of the central portions of said engaging members and 60 on the opposite side thereof from said rolls or eyes, and pivots connecting said supporting arm and engaging members.

4. A bracket, comprising engaging members arranged substantially parallel with each other and spaced apart, a supporting 65 arm extending transversely of the central portions of said engaging members, and spaced pivots separately connecting said supporting arms and engaging members eccentrically. 70

5. A bracket, comprising counterpart engaging members arranged substantially parallel with each other and spaced apart and adapted to lie with their lengths vertical, a supporting arm extending transversely of 75 the central portions of and projecting at one end materially beyond said engaging members, and spaced pivots separately connecting said supporting arms and engaging members eccentrically. 80

6. The combination of a support formed with a groove, engaging members mounted in parallel planes in said groove, extreme opposite faces of said engaging members being adapted to engage opposing walls of 85 said groove, and a supporting arm extending across and pivoted at points spaced longitudinally of said arm to said engaging members approximately midway between the ends of said members, said supporting 90 arm extending at one end beyond said groove, each engaging member being wholly revoluble on said arm independent of the other member.

7. The combination of a support formed 95 with a groove, engaging members mounted in parallel planes in said groove, extreme opposite faces of said engaging members being adapted to engage opposing walls of said groove, and a supporting arm extending 100 across and pivoted to said engaging members approximately midway between the ends thereof, said supporting arm extending at one end beyond said groove, the pivoting of the engaging members to the 105 arm being eccentric to the centers of said arms and in respect of the width thereof.

8. The combination of a support formed with a groove, engaging members adapted to be mounted at different altitudes and in 110 parallel planes in said groove, extreme opposite faces of said engaging members being adapted to engage opposing walls of said groove, and a supporting arm extending across and pivoted at points spaced longitudinally of said arm to said engaging members approximately midway between the ends of said members, said supporting arm extending at one end beyond said groove, said supporting arm and pivoting means 11 12 constituting the only connection between said engaging members.

HERBERT W. SMITH.
